G. OLSON.

CIRCUIT MAKER FOR OSCILLATING FANS.
APPLICATION FILED JULY 29, 1916.

1,245,374.

Patented Nov. 6, 1917.

UNITED STATES PATENT OFFICE.

GUSTAF OLSON, OF CHICAGO, ILLINOIS, ASSIGNOR OF ONE-HALF TO WILLARD M. McEWEN, OF CHICAGO, ILLINOIS.

CIRCUIT-MAKER FOR OSCILLATING FANS.

1,245,374.

Specification of Letters Patent.

Patented Nov. 6, 1917.

Application filed July 29, 1916. Serial No. 112,088.

To all whom it may concern:

Be it known that I, GUSTAF OLSON, a citizen of the United States of America, and a resident of Chicago, county of Cook, and 5 State of Illinois, have invented certain new and useful Improvements in Circuit-Makers for Oscillating Fans, of which the following is a specification.

The main objects of this invention are to 10 provide an improved form of circuit making device for oscillating electric fans adapted to afford a moving connection in the conductors leading from the source of electricity to the fan motor; to provide a circuit 15 making device of this kind which is suitable for fans using either alternating or direct current motors; and to provide an improved housing for the circuit making device which provides for an arrangement of detachable 20 parts whereby access to said device is rendered convenient.

An illustrative embodiment of this invention is shown in the accompanying drawings, in which—

25 Figure 1 is a side elevation of a type of electric fan wherein this improved arrangement of the circuit making device is peculiarly advantageous.

Fig. 2 is an enlarged sectional detail of a 30 portion of the fan illustrating the arrangement of the circuit making device thereon, the plane of the section being taken on the line A—A of Fig. 1.

Fig. 3 is a still further enlarged sectional 35 detail of the slip-ring construction of the circuit making device.

Fig. 4 is an end view of the slip ring construction.

Fig. 5 is a detail of one of the slip-rings. 40 Fig. 6 is an enlarged transverse sectional view taken on the line B—B of Fig. 1.

The fan illustrated in the drawings is of a type more fully described and claimed in my copending application Serial No. 112,090, 45 filed July 29, 1916, but it will be understood that this style of fan is used here merely for the sake of illustration and that the circuit making device is equally suitable to other types of oscillating fans.

50 The fan herein shown comprises blower mechanism 6 pivotally mounted on a shaft or member 7 by having lugs 8 depending from a motor casing 9 pivotally connected

to arms 10 formed on the member 7. The member 7 rotatably supports the blower 55 mechanism 6 on the base or support 11 in such manner that the blower mechanism is free to oscillate back and forth in a horizontal plane under the action of gyroscopic forces set up by tilting of the blower mechanism 6 in a vertical plane, as has been more fully described and claimed in a patent of Willard M. McEwen, No. 1,214,198, issued January 30, 1917. The mechanism for tilting the fan comprises a sleeve 12 concentrically journaled with respect to the member 7 and having formed thereon an outwardly disposed annular flange of wavelike form. The flange 13 provides a track 14 with which rollers 15 journaled on the motor 70 casing 9 are adapted to coast during the relative rotation of the sleeve 12 for tilting the blower mechanism. The rotation of the sleeve 12 is caused by a pinion 16 meshing with a rack 17 formed on the periphery of 75 the flange 13 and driven by the fan motor.

The circuit making device as applied to the above style of fan comprises three slip-rings 18, 19 and 20 mounted on a member 21 which is secured to the end of the shaft 7 80 so that the rings are rotatably suspended within an open-sided ring-shaped member 22 in such manner as to be engaged by brushes 23, 24 and 25 respectively, mounted in the sides 26 and 27 of said ring-shaped 85 member 22.

The ring-shaped member 22 has formed thereon hubs 28 and 29, the former of which is adapted to be seated within the end of the base 11 and secured thereto by a set screw 90 30, and the latter of which serves as a bearing for the shaft 7 and sleeve 12.

The slip-rings 18, 19 and 20 are formed substantially as shown in Fig. 5 and are arranged in superimposed relation upon an 95 insulating tube 31 which is rigidly secured to the member 21 in the manner shown in Fig. 3. Disks 32 of fiber, mica or other suitable material are interposed between the rings so as to properly insulate them one 100 from another. Bolts 33, 34 and 35 are connected to the rings 18, 19 and 20 respectively, by having the heads thereof seated in suitable recesses 32.1. The bolts protrude beyond the lower insulating plate 32 as indicated in the figures, and constitute binding 105

posts to which are connected respectively the conductors 36, 37 and 38 leading to the motor of the blower mechanism 6.

5 The brushes 23, 24 and 25 may be of any of the usual forms, to which are connected in a suitable manner the conductors 39, 40 and 41 leading to a connection such as a rheostat 44 (shown in dotted outline in Fig. 1) in the bottom of the support 11.

10 The hereinbefore described construction and assembly of slip-rings and brushes provides a compact and readily accessible arrangement which is suitable for either alternating or direct current uses. If it is to be used for alternating current, all three slip-rings and brushes are made use of; whereas if it is to be used for direct current, but two of the slip-rings and brushes are needed.

15 20 Plates 42 and 43 are secured to the member 22 so as to cover the open sides thereof so that the mechanism is thoroughly protected when in use, yet is quickly and easily accessible for repair or adjustment.

25 30 Although but one specific embodiment of this invention has been herein shown and described, it will be understood that numerous details of the construction shown may be altered or omitted without departing from the spirit of this invention as defined by the following claims.

I claim:

1. In an air circulating device the combination of a support provided with an open - sided, ring - shaped portion, motor-driven blower mechanism, a shaft carrying said blower mechanism and journaled on said support adjacent to said ring-shaped portion, a member secured to said shaft and rotatably suspended within said ring-shaped portion, electrical contact elements on said ring-shaped portion and said member normally urged into engagement with each other, conductors leading from the contact elements on said member to the motor of said blower mechanism, and other conductors leading from the contact elements on said ring-shaped member to a connection on said support.

50 55 60 65 2. In an air circulating device the combination of a support provided with an open - sided, ring - shaped portion, motor-driven blower mechanism, a shaft carrying said blower mechanism and journaled on said support adjacent to said ring-shaped portion, a member secured to said shaft and rotatably suspended within said ring-shaped portion, electrical contact elements on said ring-shaped portion and said member normally urged into engagement with each other, conductors leading from the contact elements on said member to the motor of said blower mechanism, other conductors leading from the contact elements on said ring-shaped member to a connection on said

support, and detachable plates adapted to cover the open sides of said ring-shaped portion.

3. In an air circulating device the combination of a support provided with an open - sided, ring - shaped portion, motor-driven blower mechanism, a shaft carrying said blower mechanism and journaled on said support adjacent to said ring-shaped portion, a member secured to said shaft and rotatably suspended within said ring-shaped portion, slip-rings mounted on said member, brushes mounted in said ring-shaped portion and normally urged into contact with the respective slip-rings, conductors leading from said slip-rings to the motor of said blower mechanism, and other conductors leading from said brushes to a connection on said support.

4. In an air circulating device the combination of a support provided with an open - sided, ring - shaped portion, motor-driven blower mechanism, a shaft carrying said blower mechanism and journaled on said support adjacent to said ring-shaped portion, a member secured to said shaft and rotatably suspended within said ring-shaped portion, slip-rings mounted on said member, brushes mounted in said ring-shaped portion and normally urged into contact with the respective slip-rings, conductors leading from said slip-rings to the motor of said blower mechanism, other conductors leading from said brushes to a connection on said support, and detachable plates arranged to cover the open sides of said ring-shaped member.

5. In an air circulating device the combination of a support provided with an open - sided, ring - shaped portion, motor-driven blower mechanism, a shaft carrying said blower mechanism and journaled on said support adjacent to said ring-shaped portion, a member secured to said shaft and rotatably suspended within said ring-shaped portion, three slip-rings arranged on said member in superimposed relation and insulated from each other, a pair of brushes arranged in one side of said ring-shaped portion and normally urged into engagement with the upper and lower slip-rings, a brush mounted on the opposite side of said ring-shaped portion and normally urged to engage the intermediate slip-ring, conductors leading from said slip-rings to the motor of said blower mechanism, and other conductors leading from said brushes to a connection on said support.

6. In an air circulating device the combination of a support, an open-sided ring-shaped member, hubs on opposite sides of said member, one adapted to engage said support for attaching said member thereto and the other serving as a bearing, motor-driven blower mechanism, a shaft carrying

said blower mechanism and journaled on said bearing, a plurality of slip-rings insulated from each other and attached to said shaft so as to be rotatably suspended within 5 said ring-shaped member, brushes on said ring-shaped member normally urged into engagement with said slip-rings, detachable plates on said member adapted to cover the open sides thereof, conductors leading from said slip-rings to the motor of said blower mechanism, and other conductors leading from said brushes to a connection on said support.

Signed at Chicago this 22d day of July, 1916.

GUSTAF OLSON.
